TUBULAR ARTICLE

Herbert S. Riddle and Charles E. Knight, Springfield, Mass., assignors to Monsanto Chemical Company, St. Louis, Mo., a corporation of Delaware

Application August 3, 1938, Serial No. 222,869

8 Claims. (Cl. 41—21)

This invention relates to tubular articles which can be used, for example, for the body of pens, pencils and the like.

Heretofore, tubular bodies for this purpose have been produced from metal tubes, such as gold or silver or from tubes of other metals coated with an attractive coating. Such articles also had been produced from plastic materials, such as cellulose nitrate or other cellulose derivatives and resins, such as a phenol formaldehyde resin. In making these articles from plastic materials, the practice has been to form a tube by boring a rod axially or by winding a decorated ribbon of the plastic material upon a mandrel and cementing the adjacent windings together by the use of a cement or solvent for the plastic material. The plastic material from which such articles have been made usually had a mottled or pearly appearance.

The present invention contemplates the production of tubular bodies having a distinctly different appearance from those bodies which it has been possible to produce using previously known methods. The article of the invention has a visible colored band or filament embedded therein, preferably of generally spiral form. Preferably, the outer surface of the article is ribbed or wavy, and these waves or ribs function like lenses so as to give the article different appearances depending upon the angle at which it is viewed.

The invention will be more clearly understood from the following description in conjunction with the accompanying drawing, in which:

Fig. 1 is a perspective view of a mandrel for use in the practice of one step in the method of producing the article of the invention;

Fig. 2 is a perspective view of a mandrel carrying the product produced by the step illustrated in Fig. 1 and illustrating the practice of the second step of the method of the invention;

Fig. 3 is a perspective view of a mandrel carrying the product produced by the second step of the method and illustrating the practice of the third step of the method of the invention;

Fig. 4 is a view similar to Fig. 3 illustrating the practice of a modification of the third step of the method of the invention; and

Fig. 5 is a longitudinal sectional view of the final product produced by the practice of the invention.

The embodiments of the invention as shown in the accompanying drawing are merely for the purpose of illustration and it is not intended that the invention shall be limited thereby. Various

modifications within the scope and spirit of the invention will be obvious and readily apparent to those skilled in the art in the light of the following description.

Referring to Fig. 1 of the accompanying drawing, the preferred practice in producing the article of the invention comprises winding an extruded filament or rod 10 of plastic material, such as cellulose nitrate, having a diameter of about 0.030" upon the mandrel 11 having a diameter of substantially the inner diameter of the tube to be produced. The windings then may be secured together by dipping in a cement or solvent for the plastic material. If desired, however, the windings may be secured to the mandrel 11 by fastening the free ends of the filament thereto. Instead of using only one filament, two or more filaments may be wound simultaneously upon the mandrel. In this way the pitch of the spiral formed by each filament can be increased.

A second filament 12 is now wound upon the body produced as illustrated in Fig. 1 so as to be positioned in the grooves 13 or hollows between adjacent windings of the filament 10. The filament 12 is colored so as to be visible in the final product and has a diameter preferably such that it will substantially fill the grooves 13. In practice, a filament 12 having a diameter of 0.010" has been found satisfactory. The filament 12 may be rayon, silk or metal wire or any colored thread or filament. The article as thus produced may then be dipped in a cement or solvent for the plastic material 10, or the filament 12 may be suitably secured to the mandrel 11. If the article is dipped in a cement or solvent for the plastic material and the article dried, a product of pleasing unique appearance is obtained.

Preferably, however, another layer of transparent plastic material is formed upon the article by winding thereupon a rod 14 of transparent plastic material as illustrated in Fig. 3. If the article as produced in Fig. 2 has not previously been dipped in a cement or solvent for the plastic material, such cement or solvent is applied upon the body of the article during the winding thereon of the rod 14 and thus fills the void between the windings 14 and the windings 10 and 12. The article is then permitted to dry and is removed from the mandrel 11.

The article thus produced will have somewhat the appearance illustrated in section in Fig. 5. The inner surface 15 will be ribbed due to the shape of the filament 10 but the size of the ribs will depend upon the tension applied to the filament 10 during winding and to other conditions

encountered during the making of the article, such as the time of applying the cement or solvent for the plastic material. Thus, under certain conditions of operation the inner surface 15 may be substantially smooth. The outer surface 16 will be composed of a continuous spiral rib 17 and will have the effect of a series of small lenses so that the filament 12 when viewed therethrough either will be clearly defined or its color diffused over a substantial area, depending upon the angle of view.

A still different appearance can be imparted to the final product by a variation of the step in the method of making the article illustrated in Fig. 3. Thus, if instead of winding the rod 14 in the same direction as the rod 10 as illustrated in Fig. 3, the rod 14 is replaced by a similar rod 14', as illustrated in Fig. 4, which is wound in a direction opposite to or crossing the winding of rod 10, an entirely different light effect is obtained and the article will have an entirely different distinctive appearance. Thus, when the articles produced as illustrated in Figs. 3 and 4 are viewed from an angle substantially perpendicular to the axis of the tube, the filament 12 will be clearly defined. When the article made as illustrated in Fig. 3 is viewed from a sharp angle, the color of the filament 12 will be diffused in an irregular more or less zig-zag pattern. If the article made as illustrated in Fig. 4 is viewed from a similar sharp angle, the color of the filament 12 will be diffused more or less uniformly throughout the body of the article. As the angle of view of this article changes from this sharp angle to approach a right angle with the axis of the tube, a point will be reached where the appearance of the tube will change almost instantly from that where the color of the filament is substantially uniformly diffused throughout the article to that where the filament is clearly defined. In the case of the article as constructed in Fig. 3, there will be no sudden change in appearance as the angle of view is similarly changed.

If the outer surface of the article produced by the procedure illustrated in Figs. 3 and 4 is machined to remove the ribs, an article of very pleasing appearance is obtained. Furthermore, the irregular or ribbed outer surface of the article may be produced by machining or molding or by other mechanical expedients.

We claim:

1. A tubular article comprising a tubular body having spaced bands of different color, and a transparent body covering the tubular body and having a ribbed outer surface. 5
2. A tubular article having a spiral shaped visible filament embedded therein, said article having a ribbed outer surface. 10
3. A tubular article having a visible spiral filament embedded therein, the adjacent convolutions of said spiral filament being spaced, said article having a ribbed outer surface. 15
4. A tubular article of unique appearance having integral inner and outer portions, said inner portion having a plurality of different bands in which the adjacent bands are of different color, said outer portion being transparent and having ribs upon its surface. 20
5. A tubular article of unique appearance having integral inner and outer portions, said inner portion having spirally arranged bands in which the adjacent bands are of different color, said outer portion being transparent and having ribs upon its outer surface. 25
6. A tubular article of unique appearance having integral inner and outer portions, said inner portion having spirally arranged bands in which the adjacent bands are of different color, said outer portion being transparent and having ribs upon its outer surface arranged in spiral configuration. 30
7. A tubular article of unique appearance having integral inner and outer portions, said inner portion having spirally arranged bands in which the adjacent bands are of different color, said outer portion being transparent and having ribs upon its outer surface arranged in spiral configuration, said bands extending at an angle to said ribs. 35
8. A tubular article of unique appearance having integral inner and outer portions, said inner portion having a plurality of different bands in which the adjacent bands are of different color, said outer portion being transparent and having ribs upon its surface, said bands extending at an angle to said ribs. 40
9. A tubular article of unique appearance having integral inner and outer portions, said inner portion having a plurality of different bands in which the adjacent bands are of different color, said outer portion being transparent and having ribs upon its surface, said bands extending at an angle to said ribs. 45
